United States Patent Office.

ALBERT H. RUSSELL, OF ADRIAN, MICHIGAN.

Letters Patent No. 79,146, dated June 23, 1868.

IMPROVEMENT IN STOCK-PUMP.

The Schedule referred to in these Letters Patent and making part of the same.

TO ALL WHOM IT MAY CONCERN:

Be it known that I, ALBERT H. RUSSELL, of the city of Adrian, State of Michigan, have invented a new and useful Improvement in Stock-Pumps; and I do hereby declare that the following is a full, clear, and exact description, which will enable others skilled in the art to make and use my invention, reference being had to the accompanying drawings, and to the letters of reference marked thereon.

My invention relates to the construction of a stock-pump, having a hydrostatic bellows placed near the bottom of the well, and operated by a platform in such a manner that by the walking of the stock upon it the water is forced up into a vessel made for the purpose.

In the drawings—

Figure 1 represents a perspective view of such a pump, its railings, platforms, &c.

Figure 2 represents a vertical section cutting the centre of the pump.

Figure 3 represents a perspective view of the hydrostatic bellows, and the lower end of the pump-log as inserted into it.

Figure 4 represents a section of the platforms cut through the red lines *x y* in fig. 1.

Like letters refer to like parts.

A represents the pump-log.

B represents one of the platforms.

C and D represent respectively the other two platforms.

R represents the railings.

T represents the water-tub.

M represents the well.

K represents the well-covering.

S represents the spout to the pump.

a and *b* represent friction-pulleys.

o represents a plug to prevent the water from rising higher than the spout.

W represents a weight, suspended by a cord, *i*, over the pulley *b*, and hangs in the well *M*.

F represents the upper, and

H the lower boards of the hydrostatic bellows.

g represents an India-rubber rim, that connects the two boards *F* and *H* of the hydrostatic bellows.

V represents two valves, covering two holes in the bottom board *H*.

U represents a rod, which is hooked at the upper end to a rope that passes over the friction-pulley *a*, and connects, by means of the two wires *m* and *n*, to the platform *B*, which is held in equipoise by the weight *W*.

j is a staple, and

f is a tongue, projecting into the staple from the under side of the platforms *C* and *D*, thus preventing them from settling lower or faster than the platform *B*.

r represents seat-blocks to prevent the lower ends of the platforms *C* and *D* from resting on the ground.

Z represents the hydrostatic bellows.

The rod *U* is firmly attached to the lower board *H* of the hydrostatic bellows, and draws it up as the platforms are depressed by the weight of the stock walking upon them.

The pump-log is secured stationary in the well by means of the well-covering *K*, and any other device desirable to hold the bottom end of it central in the well; and the bottom end of the said pump-log is inserted into the upper board, *F*, of the hydrostatic bellows, as represented.

The rod *U* at the lower end is kept central in the hollow of the pump-log by an iron cleat fastened to the under side of the upper board of the said bellows, said cleat not being represented in the drawings.

Having thus described the construction of my improved stock-pump, its operation is as follows:

The stock, seeking for water, enters either way, and upon either platform *C* or *D* while they are elevated,

as shown in the drawings, by the weight W, fig. 2. As the stock advances towards the tub T its weight depresses the platforms, and this in turn draws up the rod U and the lower board of the said bellows Z, which is now filled with water, through the openings e. The pressure of the water in the bellows Z immediately causes the valves V to drop down over the openings, and thus prevents the water from escaping downward, and is, therefore, forced up through the hollow in the pump-log, and out of the spout S into the tub T, and will continue to flow until the bellows Z is emptied, or the stock passes off, when the platforms are again raised by the weight W, and the rod U and bottom board of the bellows Z again sink down in the water and cause the bellows Z again to fill through the openings e, as before, ready for another animal.

I design this pump to be used also for drawing water, for domestic use, from cisterns and wells, substituting a treadle in place of the platforms.

Having thus described my invention, what I claim as new, and desire to secure by Letters Patent, is—

A stock-pump, in which are combined and arranged the rod U running through the bore of the pump-log A, the hydrostatic bellows Z, and the pivoted platforms C, B, and D, substantially as described.

ALBERT H. RUSSELL.
